DESIGN FOR A BOTTLE CAP

Robert E. Knudsen, Detroit, Mich.

Application March 30, 1938, Serial No. 76,195

Term of patent 14 years

To all whom it may concern:

Be it known that I, Robert E. Knudsen, a citizen of the United States, residing at Detroit, in the county of Wayne and State of Michigan, have invented a new, original, and ornamental Design for a Bottle Cap, of which the following is a specification, reference being had to the accompanying drawing, forming a part thereof.

In the drawing:

Fig. 1 is a plan view of a bottle cap showing my new design.

Fig. 2 is a side elevation thereof.

Fig. 3 is a perspective view thereof.

Fig. 4 is an elevational view of a bottle cap as it appears when crimped on the bottle.

I claim:

The ornamental design for a bottle cap, as shown and described.

ROBERT E. KNUDSEN.
